(57) **CLAIM**

(22) Filed: **Mar. 24, 2000**

The ornamental design for a reusable ice cube, as shown and described.

(51) LOC (7) Cl. **15-07**

DESCRIPTION

(52) U.S. Cl. **D15/90**

FIG. 1 is a top, front, right side perspective view of the reusable ice cube of the present invention;

(58) Field of Search D15/90; D9/345,
D9/443, 504; 62/530, 331, 529, 293

FIG. 2 is a front elevational view of the reusable ice cube of FIG. 1, the rear view being a mirror image thereof;

FIG. 3 is a left side elevational view of the reusable ice cube of FIG. 1, the right view being a mirror image thereof; and,

FIG. 4 is a top plan view of the reusable ice cube of FIG. 1, the bottom view being a mirror image thereof.

The broken lines showing of a logo in FIGS. 1 and 4 are for illustrative purposes only and form no part of the claimed design.
